ELECTRICAL HEATING ELEMENT

Thomas M. Fox, Swissvale, Pa., assignor to Edwin
L. Wiegand, Pittsburgh, Pa.

Application March 20, 1939, Serial No. 262,804

11 Claims. (Cl. 201—67)

My invention relates to electrical heating elements of the type comprising a metallic sheath in which is disposed a resistor, insulated from the sheath. In certain more specific aspects my invention is particularly useful in electrical heating elements suitable for use in electric ranges, or for cooking purposes in general. My invention has for its principal object the improvement of such heating elements.

In the drawings accompanying this application, I have shown, for purposes of illustration, several forms which my invention may assume, and in these drawings:

Figure 1 is a bottom view of a heating element embodying my invention.

Figures 2, 3, and 4 are sections taken, respectively, on the line 2—2, the line 3—3, and the line 4—4 of Figure 1, looking in the direction of the arrows, on an enlarged scale,

Figure 5 is a fragmentary view of portions of 20 a heating element such as shown in Figure 1, on an enlarged scale, and

Figures 6, 7, and 8 are fragmentary plan views illustrating respectively other heating elements embodying my invention.

The heating element illustrated in Figures 1 through 5 comprises a metallic sheath 10. The sheath is here shown as of annular or ring-form and as having disposed therein a resistor 11 suitably insulated from the sheath by insulating material 12.

The resistor 11 is here shown as made of helically wound wire, but it will be apparent to those skilled in the art that it may be made of other forms of electrical resistance material, wound or bent in other ways.

The insulating material 12, as is known in the art, may be a suitable refractory insulating material, for example, silica, or silicate, for example, zircon (zirconium silicate), or aluminum oxide, or any suitable refractory oxide or combination of refractory oxides, or any other suitable refractory insulating material, desirably of a mineral character, and desirably having good heat-conducting properties. The insulating material 12 may be mixed, if desired, with a bonding or cementing material, or mixed with clay, or any other suitable binder.

The sheath 10 is here shown as comprising a sheet metal annular channel 13, providing an annular plane wall 30, and a sheet metal annular cover plate 14, the marginal portions 15 of the sides of the channel being bent or crimped over the cover plate 14. The resultant joint or seam at a marginal portion 15 and the cover plate 14 55

need not be welded, or otherwise sealed, and, as far as certain aspects of the invention are concerned, these seams may be welded or otherwise sealed, as will be pointed out hereinafter. The sheath may be provided with studs 31, adapted to hold the element in position in an electric range.

The cover plate 14 is here shown as provided with an embossed portion 16 of sufficient circumferential length to accommodate a pair of terminals 17a, 17b, in suitably circumferentially spaced relation. The terminals 17a, 17b are here shown as having threaded shanks 18, and as having cylindrical heads 19, the latter being disposed, in this instance, at about the approximate 15 plane of the cover plate 14, and, at any rate so that the end surfaces of the heads 19 are suitably spaced from the adjacent limiting contours of the adjacent portions of the resistor 11. The shanks 18 are disposed through and spaced from the margins of apertures 20 in the top of the embossed portion 16. Washers of mica 21, or any other suitable insulating material, are here shown as surrounding the shanks 18, and disposed at the inside of the top (as viewed in the drawings) 25 of the embossed portion 16. Similar washers 22 are provided about the shanks 18, at the outside of the embossed portion 16; and each shank is here shown as provided with a nut 23 bearing against a metallic washer 24 in turn bearing 30 against the respective insulating washers 22.

The resistor 11 is here shown as having an end 25 connected to the terminal 17a, and the other end, 26, connected to the terminal 17b. The ends 25, 26 are suitably mechanically and 35 electrically connected to the respective terminals 17a, 17b, and in this instance they are disposed underneath metallic washers 27, held in place and caused to bear against the ends 25, 26 in any desired way.

40. In the embodiments illustrated, a pre-formed button 28 of insulating material is interposed between the end surface of the head 19 of each terminal 17a, 17b and the adjacent portion of the resistor 11. These buttons 28 may be formed 45 with a circumferential flange 29, so as to provide a recess in which the respective head 19 is disposed. The buttons 28 may be made of insulating material the same as or different from that in which the major part of the resistor 11 is embedded, and may be made of any suitable refractory insulating material. The buttons 28 may be baked before assembly in the heating element, or they may be preformed but unbaked, or they may be omitted and instead thereof compactable comminuted or powdered insulating ma-

terial may be utilized, the same as or different from the insulating material in which the major part of the resistor 11 is embedded.

Considering, now, the form of the resistor 11 in the embodiment of Figures 1 through 5, and tracing the resistor from the terminal 17b to the terminal 17a, the end 26 of the resistor extends downwardly slightly to the point a, in the general plane of the wound portion of the resistor 11. From the point a the general longitudinal locus 10 of the portion b of the resistor defines a circle concentric with the annular sheath 10. The portion b merges with a tangential portion t1, which continues, clockwise in this instance, and crosses over to the portion c. The longitudinal locus of the portion c defines a circle, concentric with the annular sheath, but of larger diameter than the portion b. The portion c merges with a tangent portion t2 which continues, clockwise, and crosses over to the portion d. The longitudinal locus of the portion d defines a circle concentric with the annular sheath, but of larger diameter than the portion c. The portion d merges, at e, with the end 25 which is connected to the terminal 17a.

As here shown, the portion c is disposed centrally of the cross-section of the sheath 10 and the portions b and d are disposed symmetrically with respect to the portion c.

It will be evident that the general locus of the resistor 11, as a whole, in the hereinbefore described embodiment, defines an endless loop. In prior heating elements of the type comprising an annular sheath with a resistor disposed therein, the sheath was not heated to substantially the same degree at the terminal zone as at other parts of the sheath spaced from the terminal zone, because the general locus of the resistor defined a split ring, with a considerable gap at the terminal zone. The result was that at the terminal zone the heating element was at a much lower temperature than elsewhere, for example, by test of a standard element, 300° Fahrenheit lower.

It has been found, in connection with prior heating elements, that under severe conditions of operation, the fact that the terminal zone was at a lower temperature, at times resulted in reducing the life of the heating element. It will be understood that, in operation, a heating element of the type herein illustrated, when used in an electric range, is disposed so that the wall 36 of the sheath is directed upwardly and the terminals 17a, 17b are directed downwardly, and, though the seams at the marginal portions 15, and the terminals 17a, 17b are therefore at the under side of the element, it may happen that a particularly large amount of melted grease, oil, or like cooking material, or other possibly deleterious material, may be spilled upon the heating element at the terminal zone and find its way either to the seams between the marginal portions 15 and the cover plate 14, or to the terminals. This in itself might not be objectionable, but under a conjunction of certain circumstances the deleterious material might penetrate the seams, or penetrate the terminal openings 28, through the mica washers 22, or in some other way get into the insulating material 11. Such penetration will occur principally, by way of example, if enough such material is present 20 when the heating element is cooling, perhaps because, as the element cools, a certain amount of suction is created. On heating the element again, the material will be burned out of the insulating material at all points that attain full

operating temperature, but, in the prior heating elements, at the terminal zone the material will not be burned out but will be carbonized in the insulating material. If the cycle of heating and cooling is repeated often enough, and a certain amount of grease, oil, and the like happens to be present at a certain time during the cooling phase of the cycle, the carbonized material may accumulate to such an extent as may eventually result in failure of the heating element before its normal life is reached.

On the other hand, I have found that a heating element embodying my invention may be subjected to the severest such conditions of operation without occurrence of any penetration of grease, oil, or other deleterious materials into the insulating material, and, consequently, the element may be operated to its full, normal life in spite of such severe conditions. In tests of a heating element embodying my invention it was found that the terminals, at full operating temperature, were at approximately the same temperature as the principal part of the sheath, about 800° or 850° Fahrenheit. Such temperatures are well below the burning or scaling temperature of Monel metal, for example. The mica washers were absolutely without signs of carbonization or discoloration after operation of the heating element under the conditions hereinbefore referred to. The reason for this seems to be twofold. If the deleterious material does penetrate at a seam or at the terminals, the heating element is hot enough, not only at portions away from the terminal zone but also at the terminal zone, to burn out the material, or it is hot enough so that the material is volatilized before it can penetrate.

Inasmuch as no harm is done in a heating element embodying my invention even if grease and the like do penetrate the insulating material in which the resistor is embedded, it is not only not necessary that the sheath be sealed, but the insulating material may even be exposed, as in partially sheathed heating elements, for example.

Aside from the foregoing advantages, the elimination of a relatively cold spot at and about the terminal zone or zones is of advantage where the heating element is used for the purpose of frying, or in any other instances where an even temperature all over the element is desirable. Furthermore, when the heating element is heated to a glowing temperature it will present an improved appearance because there will be no dark area, but on the contrary, the entire projected area will appear visibly uniformly heated. It will be apparent that these advantages, among others hereinafter to be mentioned, will be present irrespective of whether a seamless sheath, or a sheath having sealed seams, or any other type of sheath is utilized.

While the advantages of the heating element for cooking purposes have been described, its use is of course not limited to that purpose.

One way of constructing the heating element illustrated in Figures 1 through 5 is as follows. A suitable tool or form (not shown) analogous to the tool shown in the patent to Wiegand 1,133-347, March 30, 1915, may be provided, the tool, of course, having a resistor-supporting part which is of such shape and size that it will fit into the channel 19. This supporting part is provided with a sufficient number of pins projecting therefrom so that the resistor may be wound on and be held by the pins in the con-

figuration that it is desired it shall have in the finished heating element. The terminals 17a, 17b, are also positioned by the supporting part in any suitable way. For convenience of insertion of the buttons 28, portions of the resistor 11 at the terminal zone may be temporarily pulled aside and held by special pegs positioned laterally of the terminal zone; then the buttons 28 may be put in place over the heads 19 of the terminals; and then the aforesaid portions of the resistor may be removed from the special pegs and brought back to the position in which they cross over the buttons, as the tangents t1 and t2, as shown in Figure 5 of the drawings. The resistor, thus carried by the tool, is pressed into an open coverless channel, such as 13, before the margins 15 are crimped, the channel being partly filled to a predetermined level with comminuted or powdered insulating material, which, whether it is mixed with a binder or not, is in a plastic, or plastoid, or impressionable condition, and consequently the resistor 11 becomes embedded in the insulating material. The pins, and then the supporting part, are then withdrawn, leaving the resistor 11 embedded in the insulating material. Additional insulating material is then introduced in the channel, over the embedded resistor, and the insulating material is then compressed to a thickness which is somewhat less than its final thickness. Additional insulating material may then be built up at the terminal zone, about the lower portions of the terminals 11a, 11a, so that, eventually, when the element is completed, this additional material will fill the embossed part 16 of the cover. This additional material is also compressed. The washers 21, may then be applied, the incomplete element then appearing as indicated in Figure 5. The cover 14 is then applied, and the margins 15 are crimped over the cover. The element is then subjected to high pressure, dried, and baked.

Some examples of other forms of heating elements embodying my invention are shown in Figures 6 through 8, which also illustrate other ways in which the resistor may be disposed.

Referring now more particularly to Figure 6, there is here shown an electric heating element of the strip type comprising an elongated metallic sheath 10a which includes a channel-shaped portion 13a the margins 15a of which are bent over a cover plate 14a as already described in connection with the embodiment of Figures 1 through 5. If desired, the sheath 10a may be extended at either end to provide mounting tabs 32 having apertures 33. The heating element is provided with a pair of terminals 117a, 117b located intermediate the ends of the element. A resistor 111 is disposed within and insulated from the sheath 10a. The resistor 111 has its ends 25a, 26a connected to the terminals 117a, 117b respectively, the remainder of the resistor being here shown in the form of a helix disposed back and forth within the sheath 10a. Tracing the resistor 111, and beginning at the end 25a connected to the terminal 117a, the end 25a merges with the portion f which extends to the lower end of the sheath 10a, as viewed in the drawings, where the resistor turns 180°, continuing as the portion g. The portion g passes underneath the terminal 117b and crosses over to the portion h, the latter continuing upwardly to the upper end of the sheath, as viewed in the drawings. The resistor then turns 180°, continuing as the portion i. The portion i passes underneath the terminals 117a, 117b, crossing over to the portion j.

which continues to the lower end of the sheath. There the resistor turns 180° and continues as the portion k to the upper end of the sheath, where it turns 180° and continues as the portion l which terminates in the end 26a connected to the terminal 117b.

Referring now to Figure 7, there is here shown an electrical heating element of the strip type comprising an elongated metallic sheath 10b which includes a channel portion 13b and a cover plate 14b. In this instance the heating element is provided with a pair of terminals 217a, 217b, disposed at one end of the element. A resistor 211 is disposed within and insulated from the sheath 10b. The resistor 211 has its ends 25b, 26b connected to the terminals 217a, 217b respectively, the remainder of the resistor 211 being here shown in the form of a helix disposed back and forth within the sheath. Tracing the resistor 211, and beginning at the end 25b connected to the terminal 217a, the end 25b merges with the portion m which extends from the upper end of the sheath, as viewed in the drawings, to the lower end of the sheath, where the resistor makes a 180° turn continuing as the portion n. The portion n also extends the full length of the sheath, to the upper end, where the resistor makes a 180° turn, continuing as the portion o. The portion o extends the full length of the sheath, to the lower end, where the resistor makes a 180° turn, continuing as the portion p. The portion p also extends the full length of the sheath and merges with the end 26b which is connected to the terminal 217b.

Referring now to Figure 8, there is here shown an electrical heating element of the strip type comprising an elongated metallic sheath 10c which includes a channel portion 13c and a cover plate 14c. In this instance the heating element is provided with a pair of terminals 317a, 317b which are disposed at opposite ends of the element. A resistor 311 is disposed within and insulated from the sheath 10c, and has its ends 25c, 26c connected to the terminals 317a, 317b respectively, the remainder of the resistor being here shown as in the form of a helix disposed back and forth with the sheath. Tracing the resistor 311, and beginning at the end 25c connected to the terminal 317a the end 25c merges with the portion q which extends the full length of the sheath, to the lower end, where the resistor turns 180° continuing as the portion r. The portion r also extends the full length of the sheath, to the upper end of the sheath where the resistor turns 180° continuing as the portion s. The portion s also extends the full length of the sheath, to the lower end, where it merges with the end 26c connected to the terminal 317b.

The terminals 117a, 117b, and the terminals 217a, 217b, and the terminals 317a, 317b, may be constructed and arranged similarly to the terminals 17a, 17b of Figures 1 through 5, and it will be understood that at the terminal zones the respective resistors, in each of the embodiments shown in Figures 6 through 8, are disposed in a general plane beneath the heads of the respective terminals (corresponding to the heads 19 of the terminals 17a, 17b), analogously to the construction described in connection with Figures 1 through 5, and, accordingly, sectional views of the terminal zones of the embodiments of Figures 6 through 8, similar to the sectional views of Figures 2 and 3, have been omitted.

It will be evident that when my invention is embodied in a heating element of the strip type,

or analogous type, the heat generated in the resistor may be also substantially uniformly distributed throughout the element, along the entire length of the heating element, so that even the end portions are heated. The latter is of particular importance in cases where a heating element of relatively small dimensions, as for example a very short strip heater, is required and it is desired that the heating element shall provide desired heat close to or at the ends thereof.

In general, it will be apparent that, in a heating element of a given physical size, embodying my invention, the capacity of the element, in other words, the watt capacity, or heat generating capacity, may be increased without exceeding a given maximum sheath temperature.

On the other hand, for an element of given physical size embodying my invention, and of a capacity the same as that of an element of the same physical size but not embodying my invention, the load intensity in portions of the element spaced from the terminal zone or zones is reduced thereby increasing the overload capacity of the element. Also, for a given capacity, since the normal load intensity or concentration is reduced and the average temperature is decreased, the possibility of failure by fusion, or otherwise, is decreased.

It will be apparent from the illustrated examples hereinbefore described, that a primary desideratum is to secure a substantially uniform distribution of energy over the entire projected area of the operating face of the heating element, and that another primary desideratum is to heat the terminal zone or zones of the heating element to a predetermined degree. It will be apparent from the disclosure that these desiderata may be realized, jointly or severally, in ways other than in the particular embodiments illustrated, and in other forms of electrical resistance heating elements.

It will be understood that I do not limit myself to such temperatures as have been given hereinbefore merely by way of example. The sheath, and other metallic parts, such as the terminals, are of course made of suitable material, such as iron, or steel, or nickel, or nickel chrome, or Monel metal, or other metal alloys, or any other suitable material capable of withstanding the particular temperatures involved.

From the foregoing it will be apparent to those skilled in the art that each of the illustrated embodiments of my invention provides a new and improved electrical heating element, and accordingly, each accomplishes the principal object of my invention. On the other hand, it also will be obvious to those skilled in the art that the illustrated embodiments of my invention may be variously changed and modified, or features thereof, singly or collectively, embodied in other combinations than those illustrated, without departing from the spirit of my invention, or sacrificing all of the advantages thereof, and that accordingly, the disclosure herein is illustrative only, and my invention is not limited thereto.

I claim:

1. An electric heating element, comprising: resistor means, arranged in a linearly extended formation; terminal means, disposed laterally thereof; electrical connection between said resistor means and said terminal means; and heat-conducting electrical-insulating material enveloping said resistor means and said electrical con-

nection; said element being so constructed, that when said element is in operation, the wattage in the vicinity of said terminal means is not materially less than the average wattage, per unit of extent of said formation.

2. An electric heating element, comprising: resistor means, arranged in a substantially rectilinearly extended formation; terminal means, disposed laterally thereof; electrical connection between said resistor means and said terminal means; and heat-conducting electrical-insulating material enveloping said resistor means and said electrical connection; said element being so constructed, that when said element is in operation, the wattage in the vicinity of said terminal means is not materially less than the average wattage, per unit of extent of said formation.

3. An electric heating element, comprising: resistor means, arranged in a substantially circularly extended formation; terminal means, disposed laterally thereof; electrical connection between said resistor means and said terminal means; and heat-conducting electrical-insulating material enveloping said resistor means and said electrical connection; said element being so constructed, that when said element is in operation, the wattage in the vicinity of said terminal means is not materially less than the average wattage, per unit of extent of said formation.

4. An electric heating element, comprising: resistor means, arranged in a linearly extended formation; terminal means, disposed laterally thereof; electrical connection between said resistor means and said terminal means; and heat-conducting electrical-insulating material enveloping said resistor means and said electrical connection; sheet-metal means providing a recess in which said insulating material is disposed; said element being so constructed, that when said element is in operation, the wattage in the vicinity of said terminal means is not materially less than the average wattage, per unit of extent of said formation.

5. An electric heating element, comprising: resistor means, arranged in a substantially rectilinearly extended formation; terminal means, disposed laterally thereof; electrical connection between said resistor means and said terminal means; and heat-conducting electrical-insulating material enveloping said resistor means and said electrical connection; sheet-metal means providing a substantially rectilinear recess in which said insulating material is disposed; said element being so constructed, that when said element is in operation, the wattage in the vicinity of said terminal means is not materially less than the average wattage, per unit of extent of said formation.

6. An electric heating element, comprising: resistor means, arranged in an annularly extended formation; terminal means, disposed laterally thereof; electrical connection between said resistor means and said terminal means; and heat-conducting electrical-insulating material enveloping said resistor means and said electrical connection; sheet-metal means providing an annular recess in which said insulating material is disposed; said element being so constructed, that when said element is in operation, the wattage in the vicinity of said terminal means is not materially less than the average wattage, per unit of extent of said formation.

7. An electrical heating element, comprising: a body of insulating material having a heat transfer surface; terminal studs having portions,

disposed in said body of insulating material, opposite and spaced from said heat transfer surface; and a resistor, for heating said heat transfer surface, disposed in said body of insulating material, and having its ends in said body of insulating material and connected to said terminal portions; said resistor being so constructed and arranged with respect to said heat transfer surface that its general longitudinal locus traced from a first one of said terminal studs to the other of said terminal studs is such that an intermediate portion of said resistor traverses the body of insulating material between the end of said first terminal stud portion and the opposite portion of said heat transfer surface; said body of insulating material including a portion comprising a pre-formed member of insulating material interposed between the transverse end surface of said end of said first terminal stud portion and the adjacent said intermediate portion of said resistor, said pre-formed member having a recess in which said transverse end surface is disposed.

8. An electrical heating element for use in electric cooking apparatus, comprising: a metallic sheath having an upper heating surface upon which cooking utensils to be heated are adapted to be placed; terminals having portions disposed within said sheath, and extending downwardly through an under wall portion of said sheath; means whereby said terminals are carried by and insulated from said sheath; a resistor, for heating said heating surface, disposed within and insulated from said sheath, and having its ends connected to said terminals; and said resistor being so constructed and arranged with respect to the regions of said terminals that said resistor is adapted to heat said heating element in the regions of said terminals to a temperature high enough to vaporize cooking materials spilled upon said heating element thereby to vaporize such materials at the outside of said sheath to prevent their entry into said sheath at the terminal regions.

9. An electrical heating element for use in electric cooking apparatus, comprising: a sheet metal sheath having an upper wall providing a heating surface upon which cooking utensils to be heated are adapted to be placed, and having a seamed lower wall; terminals having portions disposed within said sheath, and extending downwardly through a portion of said lower wall; means whereby said terminals are carried by and insulated from said sheath; a resistor, for heating

said heating surface, disposed within and insulated from said sheath, and having its ends connected to said terminals; and said resistor being so constructed and arranged with respect to said sheath that said resistor is adapted to heat said heating element in the regions of said terminals and the seam of said lower wall to a temperature high enough to vaporize cooking materials spilled upon said heating element thereby to vaporize such materials at the outside of said sheath to prevent their entry into said sheath at the terminal regions or at said seam.

10. An electrical heating element for use in electric cooking apparatus, comprising: a metallic sheath having an upper heating surface upon which cooking utensils to be heated are adapted to be placed; terminals having portions disposed within said sheath, and extending downwardly through an under wall portion of said sheath; means whereby said terminals are carried by and insulated from said sheath; a resistor, for heating said heating surface, disposed within and insulated from said sheath, and having its ends connected to said terminals; and said resistor being so constructed and arranged with respect to the regions of said terminals that said resistor is adapted to heat said heating element in the regions of said terminals to a temperature high enough so that cooking materials spilled upon said heating element and which may have entered said sheath at the terminal regions are burned out.

11. An electrical heating element for use in electric cooking apparatus, comprising: a sheet metal sheath having an upper wall providing a heating surface upon which cooking utensils to be heated are adapted to be placed, and having a seamed lower wall; terminals having portions disposed within said sheath, and extending downwardly through a portion of said lower wall; means whereby said terminals are carried by and insulated from said sheath; a resistor, for heating said heating surface, disposed within and insulated from said sheath, and having its ends connected to said terminals; and said resistor being so constructed and arranged with respect to said sheath that said resistor is adapted to heat said heating element in the regions of said terminals and the seam of said lower wall to a temperature high enough so that cooking materials spilled upon said heating element and which may have entered said sheath at the terminal regions or at said seam are burned out.

THOMAS M. FOX.
